(57) **CLAIM**

The ornamental design for a clothes hanger, as shown and described.

DESCRIPTION

The hanger is intended to be mounted on the headrest support columns of a car seat.

FIG. 1 is a perspective view of a clothes hanger consisting of a rod with a hanger structure and a mounting device for mounting the hanger on a rod such as a head rest support rod of an automobile. The rod is bent backward so as to provide some space between the head rest and the hanger structure to accommodate for example a coat.

FIG. 2 is a perspective view of the clothes hanger showing the opposite side of the hanger,

FIG. 3 is a perspective view of the clothes hanger showing the hanger from the bottom rear of FIG. 1,

FIG. 4 is an elevational view of the clothes hanger showing a slightly different embodiment from FIG. 1, the only difference being the rod structure which is bent rearwardly; and,

FIG. 5 is a side view of the clothes hanger shown in FIG. 4 showing more clearly the rearwardly bent support rod providing sufficient space between a head rest and the hanger for hanging a coat.
